UNITED STATES PATENT OFFICE.

PARK Q. WRAY, OF CHICAGO, ILLINOIS.

DESIGN FOR A LAMP.

40,738.

Specification for Design. Patented June 21, 1910.

Application filed March 26, 1910. Serial No. 551,811. Term of patent 7 years.

To all whom it may concern:

Be it known that I, PARK Q. WRAY, a citizen of the United States, residing at Chicago, in the county of Cook and State of Illinois, have invented a new, original, and ornamental Design for Lamps, of which the following is a specification, reference being had to the accompanying drawing, forming a part thereof.

The figure is a perspective view of a lamp, showing my new design.

I claim:

The ornamental design for a lamp, as shown.

PARK Q. WRAY.
